W. D. CORDER

SUSPENDERS

Filed March 7, 1922

Inventor

W. D. Corder.

By *H. C. Dunlap*

Attorney

UNITED STATES PATENT OFFICE.

WAITMAN DEVER CORDER, OF PHILIPPI, WEST VIRGINIA.

SUSPENDERS.

Application filed March 7, 1922. Serial No. 541,871.

To all whom it may concern:

Be it known that I, WAITMAN DEVER CORDER, a citizen of the United States of America, and resident of Philippi, county 5 of Barbour, and State of West Virginia, have invented certain new and useful Improvements in Suspenders, of which the following is a specification.

This invention relates broadly to garment 10 supporting devices, and more specifically to an elastic connection for suspenders and the like.

The invention has for its principal object the provision of an end portion for suspenders and kindred supports embodying a resilient spring construction which affords the requisite elasticity and which, therefore, provides for the employment of inelastic webbing in the body portions of the article.

20 A further object is to provide an end structure for suspenders in which the necessary elasticity is afforded by coil springs disposed in loosely embracing relation to a cord, and in which the opposite ends of said 25 cord are rigidly held by an improved form of clamp.

With these and other objects in view, the invention resides in the features of construction hereinafter described, reference being 30 had to the accompanying drawings, in which—

Figure 1 is a front elevation of an attaching end of a suspender, partially broken away, illustrating my invention;

35 Figure 2 is a longitudinal section on line 2—2, Fig. 1;

Figure 3 is an enlarged side elevation of the clamp;

40 Figure 4 is a plan view of the cord-spacing member, enlarged; and—

Figure 5 is a lower end view of the clamp in open cord-receiving condition.

Referring to said drawings, 1 indicates a 45 webbing of inelastic material which is doubled upon itself and has its upper ends stitched together and preferably suspended by a supporting loop or ring 2 formed of wire. The lateral edges of the parallel members of the webbing are preferably stitched 50 together, forming an enclosed pocket 3, but this lateral stitching may be omitted if desired; and provided in the webbing at the lower end of said pocket are holes or eyelets 4.

55 Extending upward into the pocket through the eyelets 4 are the substantially parallel

members of a doubled or looped cord 5 which has mounted thereon below said pocket a suitable metal connector or clip, as 6, embodying a runner 7 that has slideable 60 therethrough the usual runner cord 8.

The upper ends of the looped cord 5 are received within and are rigidly held by the downwardly extending opposite end portions 9^a of a tubular yoke or clamp 9. Said 65 clamp is made of a sheet-metal blank and is of substantially U-shape, inverted, with an annular rib-like abutment or crimp 10 formed midway of the cross member thereof. The cord ends are inserted within the 70 clamp while the latter is in the open form shown in Fig. 5, following which the clamp is closed into tight-gripping relation to said ends by means of a closing-die or other suitable tool.

75 Disposed in loosely encircling relation to each of the parallel members of the cord 5 is a spiral compression spring 11 which has its upper end seated in abutting relation to the crimp or abutment 10 of the clamp 9 and 80 has its lower end resting upon a loop-like eye portion 12^a formed upon the adjacent end of a bar 12, preferably formed of wire, whereby said cord members are maintained in relatively spaced relation, said bar being 85 seated on the lower end of the pocket 3 with the eye portions thereof in register with the eyelets 4.

Due to the vertical arrangement of the opposite members of the clamp, the springs 90 are at all times maintained substantially vertical—that is to say, are prevented from unduly spreading apart to the extent that they protrude from the sides of the pocket when the side stitching is omitted. This obviously allows the employment of springs 95 of greater length than is permitted by prior suspender constructions of this general type, with a resultant increase in the elasticity of the suspender.

100 What is claimed is—

1. A suspender comprising a pocket having eyelet openings in the bottom thereof, a looped cord having its opposite end portions directed upward through said openings, a tubular sheet-metal clamp of inverted-U-shape connecting the upper ends of said cord, and spiral compression springs encircling said end portions of the cord and the adjacent ends of said clamp.

105 2. A suspender comprising a pocket having eyelet openings in the bottom thereof,

a looped cord having its opposite end portions directed upward through said openings, a tubular sheet-metal clamp of inverted-U shape connecting the upper ends of 5 said cord, and spiral compression springs encircling said end portions of the cord, said clamp having thereon an annular enlargement against which the ends of said springs abut.

10 3. A suspender comprising a pocket having eyelet openings in the bottom thereof, a looped cord having its opposite end portions directed upward through said openings, a tubular sheet-metal clamp connecting 15 the upper ends of said cord, said clamp being of inverted-U shape with an annular outstanding crimp formed midway between its ends, and a spiral compression loosely encircling each of said end portions of the 20 cord, said spring being seated at the bottom of said pocket and having its upper end disposed in abutting relation to the crimp of the clamp.

4. A suspender comprising a pocket hav-

ing eyelet openings in the bottom thereof, 25 a spacing bar resting upon the bottom of said pocket and having eye portions in register with said eyelet openings, a looped cord having its looped portion located outside said pocket and having its end portions directed upward into said pocket through said eyelets and the eyes of said bar, a tubular sheet-metal member of inverted-U shape having its terminal portions rigidly clamped upon the ends of said cord, said member having formed thereon a centrally disposed abutment, and springs loosely embracing the end portions of the cord and the terminal of said tubular member, said springs having their lower ends resting upon the eye portions of said bar and their upper ends abutting said abutment of said member.

In testimony whereof, I affix my signature in presence of two subscribing witnesses.

WAITMAN DEVER CORDER.
